UNITED STATES PATENT OFFICE

2,012,756

AUTOMATIC AND ELECTRIC FIRE ALARM

Philip Di Bella, Philadelphia, Pa.

Application October 3, 1934, Serial No. 746,736

3 Claims. (Cl. 200—142)

This invention relates to automatic electric fire alarms, and an object of the invention is to provide improved electrically operated means for sounding an alarm when the temperature of a room rises beyond a predetermined degree.

The invention also consists in the provision of an improved type of thermal switch forming a part of the alarm device and adapted to be arranged in circuit with a signal element, such as an audible signal, for example a bell or the like for automatically closing the circuit to the signal in the event of fire.

The invention together with its objects and advantages will be best understood from a study of the following description taken in connection with the accompanying drawings wherein:

Figure 1 is a view illustrating diagrammatically the application of the invention.

Figure 2 is a plan view of the switch mechanism.

Figure 3 is a view similar to Figure 2 with the cover of the switch casing removed.

Figure 4 is a longitudinal sectional view taken substantially on the line 4—4 of Figure 2, and

Figure 5 is a perspective view of a fusible element.

Referring to the drawings it will be seen that in accordance with the present invention there may be provided throughout a building one or more electrically operable audible signal devices, for example an electric bell 10. Also properly located throughout the building will be one or more thermal switches indicated generally by the reference numeral 11 and arranged in circuit with the signal devices 10 and a transformer 12 in a manner, upon closing of a switch 11 to complete the circuit to the bell 10 to set the latter in operation for giving a warning as to the presence of fire.

Each of the thermal switches 11 comprises a casing 13 which may be of any suitable material and which in the present instance is shown as being oblong and provided at the ends thereof with apertured flanges 14 whereby through the medium of fastening devices such as screws or the like the casing may be mounted to a suitable support, as for example a wall, ceiling or the like. The casing 13 is also provided with a hinged lid 15 hinged at one end to the casing as at 16 and provided at a relatively opposite end with a spring latch 17 for releasably holding the lid in closed position. The handle 18 is also provided for the lid to facilitate opening and closing of the casing. For ventilation purposes the lid 15 is provided with an opening 19 while

opposed walls of the casing 13 are provided with openings 20.

Suitably secured within the casing 13 adjacent one end thereof are spaced partitions or supporting members 21 and 22 respectively. The partition members 21, 22 are formed of any suitable material and secured to opposite sides of the partition 21 are pieces 23 of insulating material, one of which pieces is provided with circular extensions that fit in apertures provided in the partition 21 to accommodate terminal screws 24, 24' to which are secured the circuit wires 25. One of the binding screws 24 serves as a fixed contact while secured to the other of the binding screws, 24' is a spring contact member 26.

Provided in the partition 22 is a guide sleeve 27 in which is slidably an operating plunger 28 adapted to be projected for engaging the spring contact 26 with the first mentioned terminal screw 24 in completing the circuit to the bell 10.

For projecting the plunger 28 there is provided a suitably constructed trigger 29 provided with spaced ears apertured to receive a pivot bolt 30 through the medium of which the trigger 29 is pivotally mounted within the casing. Normally urging the trigger 29 to rotate in a clockwise direction for projecting the plunger 28 is a coil spring 30 one end of which is engaged with a hook 31 secured to the lower end of the trigger 29 while the other end of the spring is anchored to an end wall of the casing as shown in Figure 4.

The thermal switch includes a thermal element indicated generally by the reference numeral 32. In the present instance the element 32 consists of a flat oblong strip of celluloid 33 that extends normally transversely of the casing 13 and has the ends thereof projecting outwardly of the casing through the openings 20 in the sides of the casing. Secured to the underside of the strip 33 is a second strip 34 of celluloid the ends of which are apertured as at 35 to accommodate hooks 36, 37 respectively provided on one end wall of the casing 13 and the free end of the trigger 29 as shown in Figure 4. Obviously with the thermal strip 33 thus engaged with the hook 36, 37 the trigger 29 will be held in the position shown in Figure 4 and out of engagement with the plunger 28, against the action of a coil spring 30. Also the ends of the strip 33 projecting outwardly of the casing will be contacted by the flame before the flames are in close proximity to the casing with the result that the thermal element will be destroyed quicker by the flames than merely by the melting thereof, and consequently the switch

set in operation to close the circuit to the alarm device at the earliest possible moment.

As is obvious normally through the medium of the strip 34 engaged with the hooks 36, 37 in 5 the manner shown in Figure 4 the switch contacts 24 and 26 are disengaged for interrupting the circuit to the alarm device 10. When however the thermal element is burned or melted releasing the trigger 29, the latter under action of 10 the spring 30 will rotate in a clockwise direction in a manner to engage the plunger 28 and force the same toward the right in Figure 4 to move the spring contact 26 into engagement with the contact 24 thus completing the circuit to the 15 alarm 10, thereby setting the latter in operation.

It will be apparent that the element 32 may be easily replaced and the part reset to the position shown in Figure 4 after the fire has been extinguished thus leaving the switch 11 and the 20 system in condition for subsequent operation.

Having thus described my invention, what I claim as new is:

1. In an automatic fire alarm the combination of a fixed and a spring contact cooperable to close 25 a circuit, a plunger for engaging the spring contact with the fixed contact, guide means for the plunger, a pivotally mounted trigger adapted to move into engagement with the plunger for shifting the latter to thereby engage said contacts, 30 spring means engaged with the trigger normally urging the same into engagement with the plunger, and thermal means connected with the trigger and normally acting thereon in opposition to the spring to thereby normally maintain 35 the contacts disengaged.
2. A switch of the character described comprising a casing, a fixed contact and a spring contact in the casing and insulated therefrom, said spring contact being arranged to engage the fixed 40 contact for completing a circuit, a plunger slid-

ably mounted in the casing to engage the spring contact with the fixed contact, a trigger pivotally mounted in the casing, and adapted upon rotation in one direction to engage the plunger and force the latter into engagement with the spring contact to flex the spring contact into engagement with the fixed contact, a fusible element including a part arranged wholly within the casing, means on an end wall of the casing and the trigger connecting said part of the fusible 10 element with said wall of the casing and trigger for normally retaining the same out of engagement with the plunger, and said fusible element having a second part the opposite ends of which project outwardly of the casing through openings 15 in the side walls of the casing.

3. In a device of the character described, a casing, a fixed contact and a spring contact mounted in the casing and insulated therefrom, said spring contact being normally spaced from 20 the fixed contact, and cooperable with the fixed contact to complete a circuit, a plunger, guide and supporting means for the plunger and said spring contact having one end normally engaging one end of the plunger, a member pivotally 25 mounted in the casing and adapted to rotate in one direction to engage the free end of the plunger for shifting the same to engage the spring contact with the fixed contact, spring means anchored to a wall of the casing and connected with said 30 pivoted member for urging said pivoted member to rotate in said one direction, a fusible element extending transversely through said casing, and means on said pivoted member and a wall of the 35 casing respectively for supporting said fusible member, and in a manner to utilize said fusible member as a means for normally retaining said pivoted member against rotating in said one direction.

PHILIP DI BELLA.
